CLAIM

The ornamental design for a golf club holder insert for a golf bag, as shown and described.

DESCRIPTION

FIG. 1 is a top perspective view of a golf club holder insert for a golf bag showing my new design in use;

FIG. 2 is a top perspective view thereof;

FIG. 3 is a front elevational view, the rear elevational view being a mirror image thereof;

FIG. 4 is a right side elevational view, the left side elevational view being a mirror image thereof;

FIG. 5 is a bottom plan view thereof; and

FIG. 6 is a bottom plan view thereof in use.

The broken line showing of a golf bag in FIG. 1 and FIG. 6 and three golf clubs in FIG. 1 is for illustrative purposes only and forms no part of the claimed design.
